United States Patent Office

Des. 186,256
Patented Sept. 29, 1959

186,256

ASH TRAY

David Murdock, Cincinnati, Ohio

Application March 25, 1959, Serial No. 55,155

Term of patent 7 years

(Cl. D85—2)

Fig. 1

Fig. 4

Fig. 2

The dominant features of my new design reside in those portions shown in full lines.

I claim:

The ornamental design for an ash tray, substantially as shown and described.
